RICHARD J. MARSHALL, OF BROOKLYN, NEW YORK.

SAFETY DEVICE FOR SAD-IRONS.

1,281,045.

Specification of Letters Patent.

Patented Oct. 8, 1918.

Application filed August 24, 1917. Serial No. 187,970.

To all whom it may concern:

Be it known that I, RICHARD J. MARSHALL, a citizen of the United States, residing in the borough of Brooklyn, county of Kings, 5 and State of New York, have invented certain new and useful Improvements in Safety Devices for Sad-Irons, of which the following is a specification.

This invention relates to sad-irons and, 10 particularly, has reference to a safety device or means adapted to avoid fires resulting from overheating the iron.

Among the objects of my invention may be noted the following: to provide means in 15 connection with an electrically heated sad-iron and its holder whereby, when the iron is placed in the holder and proper attachment has been made with the service wire, the heating of the iron will at once begin; 20 to provide means by which, should the iron become excessively heated, the means holding the contacts will be automatically released, thus breaking the electric circuit and permitting the iron to cool; to provide means by 25 which, while the iron is in service, contacts may be engaged and disengaged, or the electric circuit made and broken, by merely manipulating the handle of the iron, thus enabling the iron to be heated or cooled according 30 to the will of the operator; to provide means by which, while the iron is in service, the current may be continued thereto or broken as desired, and when for any reason the iron is momentarily released, or left upon 35 the holder, or some nearby object, the current thereto will be automatically broken, thus allowing the iron to cool and avoiding accidental fires; to provide an attachment for sad-irons operating as a safety device for 40 preventing fires; to provide a means by which the service-plug may be detachably carried by the handle of the sad-iron, and the circuit between the plug and the heating coil of the iron may be broken by lifting 45 the handle to the degree desired; and to provide simple, inexpensive and effective means for carrying out the foregoing objects and bringing about the functional results noted.

With the above objects in view and others which will be detailed during the course of this description, my invention consists in the parts, features, elements and combinations thereof hereinafter described and 55 claimed.

In order that my invention may be clearly

understood, drawings are provided wherein:

Figure 1 is a side elevation of a sad-iron in its holder and embodying my invention; 60

Fig. 2 is a right-end elevation of the structure shown in Fig. 1;

Fig. 3 is a horizontal section substantially on the line 3—3 of Fig. 1.

Fig. 4 is a vertical section substantially on the line 4—4 of Fig. 1; and

Fig. 5 is an elevation of the sad-iron shown in Fig. 1 with the handle thereof thrown back to the full extent.

Referring to the drawings, the numeral 1 70 indicates the base of the iron which may be of any usual form, the same containing the usual heating-coil and other structural elements, and also the usual upstanding plug-socket 2 and rest 3. The iron is shown as 75 set upon the usual holder 4, at one end of which is secured a strip of metal 5 in any suitable manner, and to which is secured the adjustable curved strip of metal 6, arched over the handle of the iron and having 80 journaled at its free end the anti-frictional roll 7. The curved member 6 and the straight or slightly outwardly bent member 5, are composed of different metals having different coefficients of expansion in the 85 presence of heat; and the two members 5 and 6 are secured together by screws 8 passing through slots in the member 6, whereby the latter may be adjusted vertically on the member 5 so as to hold the roll 7 in the 90 proper predetermined relation to the handle of the iron. To the top of the base of the iron is secured, in any suitable manner, the strip of metal 9, or said strip may be made of any suitable heat insulating material, said 95 strip, at one end, having the vertical extension 10 which is riveted or otherwise fixed to the plug-socket 2, said extension 10 having a pin 11 set therein at a right-angle thereto. At its opposite end the strip 9 is 100 obliquely set and has the hinge-member 12 fixed thereto, the complementary hinge-member 13 being fixed to the adjacent end of the handle 14, in any suitable way, as by a depending member 15 which carries the 105 thumb-rest 16. In this manner, the handle is hinged to the base of the iron and may be thrown way back, as shown in Fig. 5, or move vertically to a limited extent so as to make and break contact of the service 110 circuit at the plug-socket 2. Secured to the strip 9 is the attaching member 17 of a re-

silient strip of metal, the free end of which is extended upwardly and curved over into a semi-loop as at 18 in position under the handle 14 near its hinged end. Thus disposed, the spring operates to normally elevate the handle a predetermined amount sufficient to break the electric circuit at the plug-socket 2. The base of the spring is secured to the spring 9 by slot and screw 19, enabling the spring to be adjusted longitudinally and thus shift its executive end 18 relatively to the handle, so as to increase tension upon the handle and normally tend to hold the same elevated the extent desired.

At its free end, the handle 14 has a U-shaped supporting member 20 fixed thereto in any suitable way, and having its arms 21 at opposite ends bifurcated to receive the journals or lugs 22 of the plug 23 of usual construction, which is adapted to enter the socket 2 and complete the electric circuit, through the heating-coil of the sad-iron, from the service line 24. To limit the movement of the handle under the stress of the spring member 18, the supporting member 20 has journaled upon the headed pin 25, a hook or gravitational-latch 26, which normally swings under and against the pin 11 projecting from the socket 2. The form of the latch is such as to enable the handle to be raised and lowered in operation without interference; but, the pin 11 is so located as to limit the movement of the handle under the stress of the spring, so as to prevent the plug 23 from being lifted in the socket 2 to an extent sufficient to disturb the coöperation or sliding relation of the plug and its points 27 with the points or contacts 28 of the socket. In other words, the plug 23 may rise in the socket 2 under stress of the spring member 18 sufficiently to break the electric circuit, but not sufficiently to cause the contacts 28 of the socket to leave the recesses or apertures in the plug 23 containing the contact 27. Thus the plug and socket are always held relatively in coöperative relation so as to readily and quickly make and break contact under opposite pressures imposed upon the handle 14 by the hand of the operator and the spring member 18. The plug member 23 is held by its journals 22 in the bifurcations of the supporting member 20, by means of the latch 29 pivoted at 30 to one of the lower arms of said supporting member, the opposite lower arm having the headed pin 31 over which the hook 32 of the latch 29 engages. Thus the plug may be readily detached from the handle of the iron and attached thereto when desired.

From the foregoing description, it will be seen that I have provided a means by which the service line can be readily attached to and detached from the iron, and

the plug thereof can be held in proper co-operative relation to the contact members of the socket carried by the iron. It will also be seen that by light pressure upon the handle, the plug 23 can be forced into the socket 2 so as to make the electric circuit to heat the iron and keep it heated. When the iron is not in use, or is laid aside momentarily, the spring member 18 will automatically lift the handle, thus lifting the plug 23 within the socket 2 and breaking the circuit through the iron. This is the safety means by which fires are prevented, since, when the iron is released and laid aside for a moment, instead of continuing to be heated, the electric circuit is broken and the iron instantly begins to cool. When it is desired to heat the iron, the plug 23 is latched to the supporting member of the handle and the iron is then placed upon the holder 4. In so doing, the handle is shoved under the anti-frictional roll of the strong spring member 6 which forces the handle downwardly carrying the plug 23 deeply into the socket 2, thus making the electric circuit, the current of which will rapidly heat the iron. If the user thoughtlessly leaves the iron in the holder with the current turned on for an indefinite period, resulting in excessively heating the iron, the heat from the latter will communicate to the holder 4 and thence to the members 5 and 6, resulting in excessively heating the said members, the unequal expansion of which will cause the curved member 6 to be pushed backwardly and to flex backwardly and upwardly, thus materially decreasing pressure of the anti-frictional roll upon the handle 14 and in turn permitting the spring member 18 to lift the handle 14 and the plug 23 within the socket 2, thus breaking the electric circuit and enabling the iron to instantly cool. Thus, two safety devices are embodied in my invention, the presence of which renders it impossible for conflagration to occur. Another great advantage of my invention is that while the iron is heated to the desired extent for certain pieces of work, it can be allowed to cool while still in operation by reduction of pressure upon the handle 14 and when it cools to the desired extent, the iron can be used without additional heating for other or lighter pieces of work. In other words, the iron can be manipulated with heavy pressure upon the handle 14, resulting in making the circuit within the plug-socket 2, and it can also be manipulated with lighter pressure upon the handle 14, permitting the circuit to be broken within the plug-socket 2. The latch 26 maintains the plug and socket in proper coöperative relation for instant circuit making, as heretofore explained.

Having thus described my invention, what

I claim and desire to secure by Letters Patent is:

1. A safety device for electrically heated sad-irons comprising a handle mounted to have freedom of movement vertically; means carried by the handle for conveying the current to the iron; and means operating upon the handle for automatically lifting the same and breaking the circuit when pressure on the handle is removed. 45
2. An electrically heated sad-iron comprising a handle and means for hinging the same to the iron at one end; means at the other end of the handle for carrying an electric plug; and a socket carried at the adjacent end of the iron for receiving the plug. 50
3. A sad-iron having a handle hinged thereto for free vertical movement; means for automatically lifting the handle when pressure thereon is removed; and means for limiting the lifting movement of the handle. 55
4. An electrically heated sad-iron carrying a plug socket; a handle hinged to the iron at one end and carrying a plug adapted to cooperate with the socket; and means connecting the handle with the iron whereby the plug and socket may be held in cooperative relation without establishing the electric circuit. 60
5. In combination with an electrically heated sad-iron having a movably mounted handle; means for conveying the current to the iron carried by the handle; means for holding the iron when not in use; and interacting automatically operating means between the handle and the holder for establishing the circuit and heating the iron when the latter is set in the holder. 65
6. In combination with an electrically heated sad-iron; means for establishing the circuit thereto; a holder for the iron; means whereby the circuit to the iron is closed when the latter is placed in the holder; and means for automatically breaking the electric circuit when the iron becomes excessively heated in the holder. 70
7. An electrically heated sad-iron having a handle pivotally mounted for vertical movement; and means whereby, when the iron is in use, the circuit to the iron may be established and interrupted at will by applying to or removing pressure from the handle. 75
8. In combination, an electrically heated sad-iron having circuit making and breaking members thereon; a non-electric holder therefor; and means between the iron and holder whereby the circuit to the former may be made and automatically broken. 80
9. In combination, an electrically heated sad-iron having a movable handle carrying a detachable circuit making and breaking device; a holder for the iron; and means operating upon the handle for establishing the circuit when the iron is placed in the holder. 85
10. In combination, an electrically heated sad-iron, a holder therefor, means for automatically establishing the circuit when the iron is placed in the holder, and means for automatically breaking the circuit when the iron becomes overheated. 90
11. A non-electric holder for electrically heated sad-irons having means for operating upon the iron whereby, when the iron is thereon, the circuit to the iron may be established and subsequently broken if the iron becomes overheated. 95
